FIG. 3.

UNITED STATES PATENT OFFICE.

CLAUD H. FOSTER, OF WICKLIFFE-ON-THE-LAKE, OHIO.

LIQUID-FUEL-HEATING DEVICE.

1,398,012.

Specification of Letters Patent.

Patented Nov. 22, 1921.

Application filed January 5, 1918. Serial No. 210,507.

To all whom it may concern:

Be it known that I, CLAUD H. FOSTER, a citizen of the United States, residing at Wickliffe-on-the-Lake, in the county of Cuyahoga and State of Ohio, have invented a certain new and useful Improvement in Liquid-Fuel-Heating Devices, of which the following is a full, clear, and exact description, reference being had to the accompanying drawings.

This invention relates to devices for preparing liquid fuel for use with internal combustion engines and, while capable of employment with liquid fuel such as kerosene, it is especially useful in starting engines with the low-grade gasoline usually employed. The invention is preferably embodied in an attachment which may be conveniently and economically applied to existing carbureters, with practically no change or modification of the latter. In the embodiments of the invention shown herein, it is contemplated that the devices will be used in connection with the starting operation and preliminarily to the closing of the ignition and starting circuits. However, it will be evident that, by suitable changes in the circuit, the devices may be employed not only preliminarily to closing the ignition circuit, but during the period when the motor is being turned over for the purpose of starting, after which a circuit including the said device may be automatically broken.

In the drawings forming part hereof, Figure 1 represents a view, partly in section and partly in elevation, of a carbureter having my invention embodied therewith; Fig. 2 is a sectional view through the float feed chamber of a carbureter of the type illustrated in Fig. 1 showing another form of my invention; Fig. 3 is a view similar to Fig. 2 of a modified form of my invention showing the same in connection with a different type of carbureter from that illustrated in Fig. 1; and Fig. 4 is a diagrammatic view of an electric circuit including my heating device.

Describing by reference characters the parts illustrated in the drawings, and with particular reference to Fig. 1, 1 represents the float-feed chamber of an ordinary type of carbureter, said chamber having the float 2 therein provided with the needle valve 3 controlling the port 4 through which the liquid fuel is supplied to said chamber by

means of the supply pipe 5. The float-feed chamber communicates with a jet nozzle 6 through a passageway 7, the jet orifice being controlled by a valve 8. 9 denotes the usual air inlet connection, provided with a butterfly valve 10, and 11 denotes the auxiliary air valve at the upper end of the jet nozzle. Above the jet nozzle and the valve 11 is the mixing chamber 12, said chamber forming part of the duct through which the combustible mixture is conducted to the engine cylinders. The outlet from the mixing chamber is controlled by the ordinary throttle valve, the operating lever for which is indicated at 13. The parts thus far described are of ordinary standard construction.

In applying my invention to a carbureter of the type above described, I may tap into the bottom of the float feed chamber a connection 14 to which a pipe 15 may be secured by means of the coupling 16. The opposite end of the pipe is connected to the bottom of a receptacle 17. This receptacle is conveniently made of two parts of metal, one of said parts carrying a threaded flange 18 to which the other section 17^a may be connected by means of a flange 19 and a coupling 20 having a flange adapted to engage the flange 19 and provided with an internal thread for securing the two parts of the casing together. A washer 21 may be inserted between the flanges 18 and 19. The casing member 17^a is provided with a socket to which an electric heater is secured, the heater being shown as a bulb 28 having the ordinary resistance therein, said bulb being of any suitable material, as glass or sheet metal, and the parts being so proportioned that an annular space is provided around the bulb, between the same and the casing. A pipe 22 connected to the top of the casing and to a connection 23 conveniently tapped into the bottom of the carbureter provides a passageway extending upwardly from the casing to the passageway 7.

With the parts constructed and arranged as described, liquid fuel from the float feed chamber will flow through the pipe 15, casing 17, pipe 22 and coupling 23 to the jet nozzle. In starting the motor, current will be supplied to the heater 28 through the conductors 24 and, owing to the comparatively small body of liquid surrounding the heater, the liquid will be heated quickly and

even brought to the vaporizing point, and heated liquid or vapor, mingled with air, may be used for starting the motor.

If desired, the switch controlling the heater circuit may be so arranged that, when the ignition button or lever is operated, the heater circuit will be automatically opened and will remain open until such time as the operator moves the switch in the opposite direction to close the circuit.

The arrangement for securing this result is illustrated diagrammatically in Fig. 4 wherein 25 denotes the spring arm contacts of a switch which is in the circuit including the storage battery 27 and the heater 28. Coöperating with the contacts 25 is a plug 29 which may be conveniently mounted in the dash 30. When the plug 29 is pushed inwardly, the circuit including the heater is closed and the liquid within the receptacle 17 may be heated. In convenient relation to the plug 29 is the stem 31 of the ignition circuit switch. This stem is provided with a pin or pins 32 adapted to engage a forked arm 33 when the stem is pulled outwardly to close the ignition circuit. This movement of the stem 31 breaks the circuit between the plug 29 and the contacts 25 and the circuit remains broken until such time as the operator pushes the plug 29 outwardly.

In Fig. 2 there is shown a modification of the invention wherein the heater is placed in the float of a float feed chamber such as shown in Fig. 1. In this case, the resistance 34 is placed within the bottom of the hollow metallic float, the conductors 35 being led through the cap 36 which covers the upper end of the stem of the valve 3. With this arrangement, gasoline or kerosene flowing from the pipe 5 through the passageway 7 is heated as it passes beneath the bottom of the float. In order to prevent accumulation of vapor within the float feed chamber, it will be preferred to connect the heater circuit with the ignition circuit in such manner that the gasoline will be heated only when the ignition circuit is closed and the starter is being operated. This will insure the supply of warm gasoline or kerosene to the motor.

In Fig. 3 my invention is shown as applied to another type of carbureter, wherein 37 denotes the float feed chamber, 38 the float and 39 the valve controlling the supply of liquid fuel to the float feed chamber, said valve being controlled by a lever 40 connected to the float and to the valve and pivoted intermediate of its ends. 41 denotes the jet nozzle, which ordinarily receives its supply from the float feed chamber through the passageways 42, and 43 denotes the connection usually provided for the application of a petcock for the purpose of draining the chamber 37. Surrounding the jet nozzle is the Venturi tube 44 which receives a supply of

air through the ordinary connection 45. 46 denotes the needle valve coöperating with the jet orifice. The parts thus far described are those of a standard type of carbureter. In applying my device to this carbureter, I may remove the petcock from the connection 43 and connect thereto a pipe 47 by means of a coupling 48. The lower end of this pipe is provided with a T-coupling 49 to the lower end of which the petcock 50 may be applied. A pipe 51 connects the central branch of the T with the bottom of the receptacle, said receptacle comprising two sections 52 and 52^a, the former section being provided with the connection 53 to which the pipe 51 is secured and the latter section carrying a heater 54 which may be similar to the heater 28 and similarly connected to its section. The two sections 52 and 52^a will be connected by means of a coupling 55 similar to the coupling 20. A pipe 56 connects the upper end of the section 52^a with the passageway 41^a of the jet nozzle.

In both forms of my invention, shown in Figs. 1 and 3, my device is inserted between the float feed chamber and the jet nozzle of the carbureter and the liquid fuel circulates from the bottom of the float feed chamber through the heating receptacle to the jet nozzle. In all three embodiments of the invention, the device is applied to a carbureter of standard construction with practically no change therein. Furthermore, the device is comparatively inexpensive of production while extremely efficient in operation, the parts being so constructed and arranged that only a small demand is made upon the storage battery for the purpose of heating the liquid to facilitate starting the motor.

Having thus described my invention what I claim is:

1. The combination, with the float feed chamber and the jet nozzle of a carbureter, of a receptacle beneath the float feed chamber, an inlet pipe extending from the bottom of the float feed chamber to the bottom of said receptacle, an outlet pipe connecting the top of the receptacle with the jet nozzle, and an electric heater in said receptacle interposed between said inlet and outlet pipes.

2. The combination, with a carbureter including a float feed chamber and a jet nozzle, of a conduit extending between the float feed chamber and the jet nozzle, a receptacle in said conduit, said receptacle consisting of a sectional casing, an electric heater carried by one of the casing sections and means for detachably connecting said casing sections.

3. The combination, with a carbureter including a float feed chamber and a jet nozzle, of a conduit extending between the float feed chamber and the jet nozzle, a receptacle in said conduit, said receptacle consisting of a sectional casing, means for detachably con-

necting the casing sections, and an electric heater carried by one of said sections and adapted to project into the other section and to provide with the casing a heating chamber extending around said heater.

4. The combination, with a carbureter including a float feed chamber and a jet nozzle, of a conduit extending between the said chamber and nozzle, a receptacle in said conduit, and an electric lamp extending into said receptacle and forming with the interior thereof a circulating space for liquid fuel.

5. The combination with a fluid fuel receptacle and the throttle duct of a mixing device for internal combustion engines, of a conduit for conducting fluid fuel from said receptacle to the throttle duct, a sectional receptacle in the conduit, an electric heating

element disposed within said receptacle, and connections for supplying electric current to 20 said element.

6. The combination, with a fluid fuel receptacle and the throttle duct of a mixing device for internal combustion engines, of a conduit for conducting fluid fuel from said 25 receptacle to the throttle duct, a sectional receptacle in the conduit, an electric lamp carried by one of the receptacle sections and forming with the inner wall of the second receptacle a space for the circulation of fluid 30 fuel, and connections for supplying electric current to said lamp.

In testimony whereof, I hereunto affix my signature.

CLAUD H. FOSTER.
